UNITED STATES PATENT OFFICE.

HENRY GEORGE DEBNAM, OF LONDON, ENGLAND.

ROTARY INTERNAL-COMBUSTION ENGINE.

1,308,339.

Specification of Letters Patent.

Patented July 1, 1919.

Application filed April 11, 1917. Serial No. 161,314.

To all whom it may concern:

Be it known that I, HENRY GEORGE DEBNAM, a subject of the King of Great Britain, residing at 14 and 15 Atherstone Mews, 5 Cromwell road, London, S. W., England, have invented new and useful Improvements in Rotary Internal-Combustion Engines, of which the following is a specification.

This invention relates to improvements in 10 rotary internal combustion engines.

According to this invention a drum is mounted upon a shaft and carries a number of pistons which are caused to move radially and project from the periphery of the drum 15 by a cam path into which projections from the pistons enter. A casing or cover surrounds the drum and is shaped similarly to the cam path so that the heads of the pistons are always in contact with the casing. 20 Each piston is preferably hollow and is divided into two chambers. On one side of each piston are two ports which, when the piston is in its extreme outward position, register with ports in a passage in the drum 25 connected to the gas supply and so allow the explosive charge to enter one chamber of the piston and to pass to the combustion chamber.

The shaft upon which the drum is mounted is hollow and passages are provided leading from it to the passages in the drum connecting with the gas supply, and the throttle valve is preferably situated inside the shaft. 30

The inner ends of the majority of the pistons are used for pumping and compressing the gas, while the remainder are employed for drawing oil from an oil reservoir. 35

In some cases a number of similar drums carrying pistons are mounted side by side 40 upon a shaft.

The accompanying drawings show apparatus made in accordance with this invention.

Figure 1 is a longitudinal vertical section 45 of the engine.

Fig. 2 is a vertical section of one of the pistons.

Fig. 3 is a section of a piston at right angles to Fig. 2.

Fig. 4 is a section on the line 4-4, Fig. 3.

Fig. 5 is a section on the line 5-5, Fig. 3.

Fig. 6 is a vertical section of one of the pistons of the air compressor, and Fig. 7 is a vertical section of one of the pistons of

this compressor which is used for distributing oil.

Fig. 8 is a section of a block in the hollow shaft.

Fig. 9 is a transverse section partly in elevation of the drum. Figs. 10 and 11 are vertical and horizontal sections of the same, the hollow shaft being omitted.

Fig. 12 is a transverse section partly in elevation of the casing and part of the drum.

Fig. 13 is a vertical section partly in elevation of the casing.

Fig. 14 shows a cylinder in which the piston which pumps the oil works.

Fig. 15 shows a method of igniting the charge.

Fig. 16 is a section and Fig. 17 is a section on the line 17-17, Fig. 16, of a distributing valve.

Fig. 18 shows an oil valve.

A drum 1 is mounted upon a hollow shaft 2 and carries pistons 3 which project from the periphery of the drum 1 into a casing 4 which surrounds the outer part of the drum, while the inner part is covered by the frame of the engine. In the frame on each side of the engine on each side of 80 the pistons are cam paths 5 (see Fig. 12) into which enter balls 6 (see Figs. 2 to 5) carried by the pistons 3. The inner wall 7 (Figs. 12 and 13) of the casing 4 is similarly shaped to the cam paths 5 so that as the pistons are caused to move in and out of the drum 1 by the cam paths 5 their heads are always in contact with the inner wall 7 of the casing 4.

Each piston 3, as shown in Figs. 2, 3, 4 90 and 5, is hollow and is divided longitudinally into two chambers 8 and 9 by a partition 10. In each piston are two ports 11 and 12; when the piston is in its extreme outward position the port 11 registers with a port 111 communicating with a passage 121 which leads to the hollow shaft 2 and thence to a gas reservoir 13 through a passage 131, and allows the explosive charge to enter the chamber 8 of the piston 3 and to pass through the port 12, through another port 141, to a passage 14 in which is a non-return valve 15, to a combustion chamber formed between the drum 1, the casing 4 and the part of the piston 3 protruding from the drum. The inner end of each piston 3 works in a cylinder 16 which is in communication with a vaporizer 17 by means of a

passage 18, an annular chamber 181 and a pipe 171; in the passage 18 is a non-return valve 19. The annular chamber 181 communicates by a passage 182 with an annular chamber 421 in the drum 1 thus allowing gas to flow to the drum for cooling purposes. As the piston 3 moves outward it draws gas from the vaporizer 17, past the valve 19, into the cylinder 16, and on its return motion 5 expels it from the cylinder 16 through a valve 20, and so through the hollow shaft 2 into the gas reservoir 13. The reservoir 13 has a control valve 132, which, when the pressure rises in the reservoir, cuts off the 10 supply from the vaporizer through a rod 133 and an arm 134.

In the hollow shaft 2 is a throttle valve 21 by means of which communication between the hollow shaft and the passage 121 15 is shut off.

On the outer end of each of the pistons 3 are side plates 22 and end plates 23 which are continually pressed outward by means of springs 24 and 25 respectively, so that the 20 end of the piston makes a close joint with the drum 1 and casing 4.

The exhaust gases pass through apertures 26 in the inner wall and apertures 27 in the outer wall of the casing to an annular chamber 28 from which they pass to the outer air.

In the engine shown in the drawings there are six pistons, five of which are used for compressing gas as above set out, the remaining one being used for pumping oil from an oil reservoir 29. The cylinder 30 in which this piston works is shown in Fig. 14. As the piston moves outward it draws oil from the oil reservoir 29, through pipes (not shown) and through a non-return valve 32 35 and openings 33, into the cylinder. On the inward stroke of the piston the oil is expelled partly through a passage 35 in which is a non-return valve 36 to a chamber 37 in the hollow shaft 2 situated between a block 38 and the throttle valve 21, and is led 40 through a hollow rod 39, which actuates the throttle valve 21, to an air compressor hereinafter described. The rest of the oil passes out through a passage 40 past a non-return 45 valve 41 into an annular chamber 42. The annular chamber 42 is connected to a passage 43 in which is a spring-controlled valve 44 which opens when the pressure is excessive and allows the oil to return to the oil reservoir 29. The chamber 42 communicates 50 with the other pistons 3 through ports 45 and 46 in the cylinders 16 and pistons 3 respectively. The oil passing through the ports 45 and 46 fills the chambers 9 of the pistons. Small apertures are formed in the walls of the pistons through which the oil passes for lubricating purposes.

Ignition may be effected by means of the apparatus shown in Fig. 15. This apparatus is fixed to the casing at 471 in such a

manner that a part 47 carrying a ball 48 stands in the path of the pistons 3. As one of the pistons passes over the ball it compresses a spring 49 and presses a contact 50 against another contact 51 which is connected by a lead 52 to a bus bar 53. When the ball 48 is released by the piston 3 it is pressed outward again by the spring 49 and as the contacts 50 and 51 move apart a spark is formed firing the charge.

In order to aid the starting of the engine connection may be made from the four points 54 in the outer casing to the gas reservoir 13 by a passage 55 leading to a valve 56 shown in Figs. 16 and 17; and thence by a passage 57. On the spindle 58 of the valve 56 is a sleeve 59 carrying pins 60 which engage with a split plug 61, which, when a handle 62 is actuated, turns and opens or closes communication between the two passages 55 and 57.

In some cases liquid fuel or crude oil may be supplied to the jacket 63 of the casing 4 and vapor from the jacket is led to the vaporizer 17. Air is allowed to enter the vaporizer, a mixture of air and vapor being drawn from it by a compressor.

The mode of working the engine is as follows:—

When the pistons 3 are in their extreme 95 outward position the explosive charge flows from the gas reservoir 13, through the hollow shaft 2, past the throttle valve 21 and through passages 121, ports 111 and 11, to the pistons 3, and out through ports 12 and 141, passage 14 and non-return valve 15, into the combustion chamber formed in the casing behind the pistons 3. As the pistons move they are drawn inward a small distance by means of the cam paths 5, closing 100 the ports 12 and 11. The charges are then fired, and as the drum 1 revolves the pistons pass over the apertures 26 and 27 leading to the annular chamber 28, the products of combustion being swept into the chamber 105 by the following pistons, which are then caused by the cam path to enter wholly into the drum.

The engine as shown in Figs. 1 to 18 is 110 suitable for use with motor vehicles, in which case an air compressor having pistons moved radially by a cam path similarly to the engine is mounted upon the hollow shaft 2 and is controlled by the friction clutch 64. In 115 this compressor are five pistons 65 as shown in Fig. 6, and one piston 66 as shown in Fig. 7. The pistons 65 are employed for compressing the air while the piston 66 is employed for circulating the oil which is supplied to it, as above described, through 120 the hollow rod 39. Air is drawn through passages 67 past a non-return valve 68 to cylinders 69, and on the downward stroke of the pistons 65 is expelled past a valve 70, 125 past another valve 71, to a compressed air 130

reservoir 72. A passage 73 leads from the compressed air reservoir 72 to the hollow shaft on that side of a block 74 fixed to the hollow shaft remote from the engine. The 5 compressed air passes through another block 75, which is shown in section in Fig. 8, and presses a piston 76 against the action of a spring 77. When the pressure of air is sufficient to overcome the spring, the parts of 10 the clutch 64 are separated and thus stop the driving of the compressor.

The engine may be worked as a Diesel engine in which case the compressed air is passed to the backs of the pistons as before 15 described and valves are provided in the casing to allow of the admission of the oil; such a valve is shown in Fig. 18. In this figure 78 is a ball valve to which oil is admitted through a pipe 79. A projection 80 20 extends into the path of the pistons 8 which depresses a projection 81 against the action of a spring 82 thereby actuating a lever 83 which moves the ball 78 from its seating, allowing the oil to pass behind the piston. 25 A dynamo may be driven from the disk 100 on a shaft 101 having a pulley 102 driven from a pulley 103 on the hollow shaft.

I do not herein claim the novel features 30 of the compressor hereinbefore described and shown in the accompanying drawings.

Claims to the novel features of said compressor are made in my application for patent, Serial No. 237,137, filed May 28, 1918, which is a division of the application for 35 this patent.

What I claim is:

1. In a rotary internal combustion engine, a casing inclosing a drum mounted upon a shaft and carrying a number of pistons controlling the admission of gas to a passage in the drum leading to combustion chambers, a non-return valve in the passage, and a cam path causing each piston to move radially and to form one side of a combustion 45 chamber.

2. In a rotary internal combustion engine, a casing inclosing a drum mounted upon a shaft and carrying a number of pistons controlling the admission of gas to a passage in the drum leading to combustion chambers, a non-return valve in the passage, and continually making contact with the inner wall of the casing, and a cam path similarly shaped to the inner wall of the casing causing each piston to move radially and to form one side of a combustion chamber.

3. In a rotary internal combustion engine, a casing inclosing a drum mounted upon a shaft and carrying a number of hollow pistons controlling the admission of gas to a passage in the drum leading to combustion chambers, a non-return valve in the passage, and a cam path causing each piston to move radially and to form one side of a combustion 60 chamber.

4. In a rotary internal combustion engine, a casing inclosing a drum mounted upon a shaft and carrying a number of hollow pistons controlling the admission of gas to a passage in the drum leading to combustion 70 chambers, a non-return valve in the passage, and continually making contact with the inner wall of the casing and a cam path similarly shaped to the inner wall of the casing causing each piston to move radially and to 75 form one side of a combustion chamber.

5. In a rotary internal combustion engine, a casing inclosing a drum mounted upon a shaft and carrying a number of pistons controlling the admission of gas to a 80 passage in the drum leading to combustion chambers, a non-return valve in the passage, a cam path causing each piston to move radially and to form one side of a combustion chamber, and means causing one of the pistons to pump gas.

6. In a rotary internal combustion engine, a casing inclosing a drum mounted upon a shaft and carrying a number of pistons controlling the admission of gas to a 90 passage in the drum leading to combustion chambers, a non-return valve in the passage, and continually making contact with the inner wall of the casing, a cam path similarly shaped to the inner wall of the casing causing each 95 piston to move radially and to form one side of a combustion chamber, and means causing one of the pistons to pump gas.

7. In a rotary internal combustion engine, a casing inclosing a drum mounted upon a 100 shaft and carrying a number of hollow pistons controlling the admission of gas to a passage in the drum leading to combustion chambers, a non-return valve in the passage, a cam path causing each piston to move radially and to form one side of a combustion 105 chamber, and means causing one of the pistons to pump gas.

8. In a rotary internal combustion engine, a casing inclosing a drum mounted upon a 110 shaft and carrying a number of hollow pistons controlling the admission of gas to a passage in the drum leading to combustion chambers, a non-return valve in the passage, and continually making contact with the inner wall of the casing, a cam path similarly shaped to the inner wall of the casing causing each piston to move radially and to form one side of a combustion chamber, and means causing one of the pistons to pump 115 gas.

9. In a rotary internal combustion engine, a casing inclosing a drum mounted upon a shaft, and carrying a number of pistons controlling the admission of gas to combustion 125 chambers, a cam path causing each piston to move radially and to form one side of a combustion chamber, and means causing one of the pistons to pump oil.

10. In a rotary internal combustion engine,

gine, a casing inclosing a drum mounted upon a shaft and carrying a number of pistons controlling the admission of gas to combustion chambers and continually making contact with the inner wall of the casing, a cam path similarly shaped to the inner wall of the casing causing each piston to move radially and to form one side of a combustion chamber, and means causing one of the pistons to pump oil.

11. In a rotary internal combustion engine, a casing inclosing a drum mounted upon a shaft and carrying a number of hollow pistons controlling the admission of gas to combustion chambers, a cam path causing each piston to move radially and to form one side of a combustion chamber, and means causing one of the pistons to pump oil.

12. In a rotary internal combustion engine, a casing inclosing a drum mounted upon a shaft and carrying a number of hollow pistons controlling the admission of gas to combustion chambers and continually making contact with the inner wall of the casing, a cam path similarly shaped to the inner wall of the casing causing each piston to move radially and to form one side of a combustion chamber, and means causing one of the pistons to pump oil.

13. In a rotary internal combustion engine, a casing inclosing a drum mounted upon a shaft and carrying a number of hollow pistons divided into chambers, the one to receive gas and the other to receive lubricating oil for lubricating the pistons, which pistons control the admission of gas to combustion chambers, and a cam path causing each piston to move radially and to form one side of a combustion chamber.

14. In a rotary internal combustion engine, a casing inclosing a drum mounted upon a shaft and carrying a number of hollow pistons divided into chambers, the one to receive gas and the other to receive lubricating oil for lubricating the pistons, which pistons control the admission of gas to combustion chambers and continually make contact with the inner wall of the casing, and a cam path similarly shaped to the inner wall of the casing causing each piston to move radially and to form one side of a combustion chamber.

15. In a rotary internal combustion engine, a casing inclosing a drum mounted upon a shaft and carrying a number of hollow pistons divided into chambers, the one to receive gas and the other to receive lubricating oil, which pistons control the admission of gas to combustion chambers, a cam path causing each piston to move radially and to form one side of a combustion chamber, means causing one of the pistons to pump gas and means causing one of the pistons to pump oil for lubricating the pistons.

16. In a rotary internal combustion engine, a casing inclosing a drum mounted upon a shaft and carrying a number of hollow pistons divided into chambers, the one to receive gas and the other receive lubricating oil, which pistons control the admission of gas to combustion chambers and continually make contact with the inner wall of the casing, a cam path similarly shaped to the inner wall of the casing causing each piston to move radially and to form one side of a combustion chamber, means causing one of the pistons to pump gas and means causing one of the pistons to pump oil for lubricating the pistons.

17. In a rotary internal combustion engine, a casing inclosing a drum mounted upon a shaft, pockets in the drum, hollow pistons in the pockets, ports in the walls of the pockets, ports in the pistons adapted to coincide with the other ports and allow the admission of gas to combustion chambers, and a cam path causing each piston to move radially and to form one side of a combustion chamber.

18. In a rotary internal combustion engine, a casing inclosing a drum mounted upon a shaft and carrying a number of pistons controlling the admission of gas to combustion chambers and adapted to be acted upon laterally by the gas pressure, and a cam path causing each piston to move radially.

19. In a rotary internal combustion engine, a casing inclosing a drum mounted upon a shaft, pockets in the drum, hollow pistons in the pockets, ports in the walls of the pockets, ports in the pistons adapted to coincide with the other ports and allow the admission of gas to combustion chambers, and a cam path similarly shaped to the inner wall of the casing, causing each piston to move radially and to form one side of a combustion chamber.

20. In a rotary internal combustion engine, a casing inclosing a drum mounted upon a hollow shaft and carrying a number of pistons controlling the admission of gas to combustion chambers, a cam path causing each piston to move radially and to form one side of a combustion chamber and a throttle valve in the hollow shaft adapted to regulate the supply of gas to the engine.

21. In a rotary internal combustion engine, a casing inclosing a drum mounted upon a hollow shaft and carrying a number of pistons controlling the admission of gas to combustion chambers, a cam path causing each piston to move radially and to form one side of a combustion chamber, means causing one of the pistons to pump gas, and a throttle valve in the hollow shaft adapted to regulate the supply of gas to the engine.

22. In a rotary internal combustion engine, a casing inclosing a drum mounted upon a hollow shaft and carrying a number of pistons controlling the admission of gas to combustion chambers, a cam path causing each piston to move radially and to form one side of a combustion chamber, means causing one of the pistons to pump oil, and a throttle valve in the hollow shaft adapted 10 to regulate the supply of gas to the engine.

23. In a rotary internal combustion engine, a casing inclosing a drum mounted upon a hollow shaft and carrying a number of hollow pistons divided into chambers, the 15 one to receive gas and the other to receive lubricating oil for lubricating the pistons, which pistons control the admission of gas to combustion chambers, a cam path caus-

ing each piston to move radially and to form one side of a combustion chamber, 20 and a throttle valve in the hollow shaft adapted to regulate the supply of gas to the engine.

24. In a rotary internal combustion engine, a casing inclosing a drum mounted upon a hollow shaft, pockets in the drum, hollow pistons in the pockets, ports in the walls of the pockets, ports in the pistons adapted to coincide with the other ports and allow the admission of gas to combustion chambers, a cam path causing each piston to move radially and to form one side of a combustion chamber, and a throttle valve in the hollow shaft adapted to regulate the supply of gas to the engine. 25 30

HENRY GEORGE DEBNAM.
